UNITED STATES PATENT OFFICE.

ROSE HANSKAT, OF CHICAGO, ILLINOIS.

GARMENT.

Application filed August 22, 1925. Serial No. 51,849.

This invention relates to garments and more particularly to a nether garment combining the functions of a brassière and a stayless hip reducing corset.

As is well known to those familiar with the art, hip reducing corsets employing elastic features for causing the corset to conform to the body of the wearer to support the abdomen and at the same time constrict the hips have been commonly employed, but these garments with which I am familiar are possessed of several disadvantages, the main disadvantage being that the elastic sections have a tendency to creep over the enlarged portions at the hips of the wearer and thus cause the entire corset to elevate with the result that it becomes wrinkled and uncomfortable and ceases to perform its proper functions. This feature has a further disadvantage when the corset is provided with an upper section, replacing the ordinary brassière in that the upward movement of the corset has a tendency to cause the brassière section to likewise move upwardly with the result that it becomes exposed through a thin dress, rendering the wearer conspicuous as well as uncomfortable. Accordingly, an important object of this invention is to provide means whereby the corset section is at all times maintained at its proper level and puckering of the elastic sections over the hips is prevented.

A further object of the invention is to provide means for relieving the rear garter or stocking support of a corset of this type of the strain which is ordinarily applied thereto, which strain so positions the fastener of the garter that it is often unfastened as the wearer seats herself, thus destroying its function of supporting the stocking as well as its added function of retaining the rear portion of the garment in its proper position.

A further object of the invention is to provide a corset in which the elastic sections are so designed that both the corset and brassière sections are caused to properly fit upon and engage with the body of the wearer.

These and other objects I attain by the construction shown in the accompanying drawings, wherein for the purpose of illustration is shown a preferred embodiment of my invention and wherein—

Figure 1 is a perspective of a corset and

brassière constructed in accordance with my invention;

Figure 2 is a perspective view showing the garment as applied to the body;

Figure 3 is a fragmentary inside elevation of the body showing the manner of attaching the garter elastics to the elastic panels.

Referring now more particularly to the drawings, the corset comprises a front section 10, a rear section 11 and side sections 12 and 13. The front section 10 is so formed that it will conform to the shape of the wearer and is formed entirely of inelastic material. The rear section is likewise composed entirely of inelastic material with the exception of an elongated triangular gusset 14 of elastic material extending from the lower end of the back section to the waist line. This gusset is arranged centrally of the back and is elastic only in a direction transversely of the back. Depending from the lower edge of the rear section midway between the edge margins thereof and the lower end of the gusset are the usual supporting elastics 15.

The side sections 12 and 13 are identical with the exception of the fact that one of these side sections 13 is provided along one marginal edge with fasteners for coaction with the fasteners carried by one side margin of the front section, as indicated at 16. Each side section has an upper rectangular panel 17 of semi-elastic material, such as some finely knitted fabric and the intermediate panel 18 of inelastic material and the lower elastic trapezoidal panel 19 of substantially the same length as the gusset 14 of the rear section and like the gusset of the rear section elastic only transversely of the section. The sides 20, 21 of this trapezoidal panel 19 converge only slightly toward the upper end thereof with the result that the upper end 22 of the panel is relatively broad. The trapezoidal panel 19, when in applied position, will lie directly over the hip of the wearer and will extend below the point of greatest diameter.

It will be noted that by employing this construction at and slightly above the waist line, a solid band of material is provided. In applying the corset, care should be taken to hook the corset from the bottom to the top, as the elastic section, places a strain against the abdomen, which will cause the abdomen to be lifted as the corset is hooked

in this manner. The solid band above referred to and which is completed at the sides of the garment by the inelastic panels 18 will confine the diaphragm and coact with 5 the elastic lower section to maintain the body in its proper position. The semi-elastic panels 17 at the upper ends of the side sections, when the garment is in applied position, will lie immediately beneath the 10 arm pit of the wearer and will give sufficiently to allow for slight differences in the size of the bust of the wearer. Applied to a person having a small bust, this panel will not change its shape but where the person 15 has a large bust, the panel will be elongated in a direction circumferential to the garment with the result that excess measurements in any given size of garment will be taken care of.

20 The gusset 14 and elastic panels 19 hereinbefore described will permit the lower portion of the garment to conform exactly to the shape of the body of the wearer. The panel 19 provides not only a circumferential 25 constriction at the abdomen but likewise exerts a continuous upward pull from the center of the front panel with the result that there is a constant tendency to elevate the abdomen as well as to constrict the same.

30 The rear section of the garment is so cut that it conforms to the shape of the body at the bust and the elastic gusset 14 thereof will allow for any expansion due to bending of the body, as in stooping or sitting.

35 Stooping or sitting movements will, of course, tend to cause upward sliding of the elastic sections when they are placed under strain and for this reason, I have applied to the inner face of the panels 19 at the 40 center thereof an upwardly tapering strip of fabric 23 which has its upper end attached to the inelastic panel 18 and which is attached throughout its length to the elastic panel 19. This strip forms a support 45 and a means of attachment for a garter 24 which, by its engagement with the stocking of the wearer, will maintain a steady downward strain, effectually preventing its creeping. Not only does the strip 23, in combination with the garter 24, prevent its creeping but it also serves to cause the elastic section to maintain its engagement with the 50 hip and to prevent the tendency of the elastic section to stretch vertically which, in time, would cause in the elastic section a pucker or bulge, preventing its fitting properly at the hip. By tapering this strip from the bottom to the top thereof, I prevent division of the elastic panel into what would 55 be, in effect, a pair of narrow V-shaped gussets for I have found that a V-shaped gusset, instead of applying its strain in a direct line circumferentially of the garment, as it is necessary that the panel 19 provide

strain, has a tendency to an upward strain 65 at the narrow end of the gusset. In other words, the divergence of the sides of a V-shaped gusset necessitates that in order to obtain maximum elasticity, the strain come from a point substantially at right angles 70 to the sides of the gusset. The front section 10 of the garment will, of course, be provided with the usual garter elastics 25.

It will be obvious that a garment of this character will closely conform to the shape 75 of the body of the wearer and will have a tendency to constrict the abdomen and hip and to support the abdomen and at the same time will not have a tendency to crawl upwardly upon the body of the wearer. 80

It will furthermore be obvious that the construction hereinbefore set forth is capable of a certain range of change and modification without materially departing from the spirit of the invention and I accordingly do not limit myself to such specific structure except as hereinafter claimed.

I claim:—

1. A stayless garment combining the functions of a corset and brassière including 90 front and rear sections, the front section being inelastic the rear section having an elastic gusset extending from the lower end thereof to the waist line of the garment, said gusset being relatively narrow at its lower 95 ends and tapering from its lower to its upper end and side sections each including an inelastic panel arranged immediately above the waist line and a lower elastic panel coextensive with the gusset, which, in the applied position of the garment, immediately 100 overlies the hips of the wearer, said gusset and elastic panels being only elastic circumferentially of the garment, the upper ends of said side sections comprising panels of 105 semi-elastic material yielding under strain to permit enlargement of the bust section of the garment.

2. A stayless garment combining the functions of a corset and brassière including 110 inelastic front and rear sections, the rear section having an elastic gusset extending from the lower end thereof to the waist line of the garment and side sections each including an inelastic panel arranged immediately 115 above the waist line and a lower elastic panel co-extensive with the gusset, said gusset and elastic panels being only elastic circumferentially of the garment, a narrow inelastic strip applied to each of 120 the elastic panels and connected at their upper ends to the inelastic panels of the side sections and garters secured to the lower ends of said inelastic strips.

In testimony whereof I hereunto affix my 125 signature.

ROSE HANSKAT.
